UNITED STATES PATENT OFFICE.

HENRY HUNGERFORD, OF NORWALK, CONNECTICUT, ASSIGNOR, BY MESNE ASSIGNMENTS, TO THE UNITED STATES COTTON SEED CLEANING COMPANY, OF NEW YORK, N. Y.

GRINDING-MILL.

SPECIFICATION forming part of Letters Patent No. 295,764, dated March 25, 1884.

Application filed September 15, 1881. (No model.)

To all whom it may concern:

Be it known that I, HENRY HUNGERFORD, of Norwalk, in the county of Fairfield and State of Connecticut, have invented a new and useful Improvement in Grinding-Mills, of which the following is a full, clear, and exact description.

My improvements relate to cylinder and concave mills for reducing grain and other materials, and have the special object to save regrinding of the materials, as heretofore necessary in that class of mills.

In the drawings, Figure 1 is a vertical transverse section of the improved mill. Fig. 2 is a horizontal section on line $\alpha\alpha$ of Fig. 1. Fig. 3 is a detail section showing the construction of the revolving grinder. Fig. 4 is a detail section showing one end of the stationary grinder, and Fig. 5 shows the separate portions or sections of which the grinders are formed.

A is the supporting-frame of the mill, covered by a curb, B, that supports a hopper, C, all of which parts may be of any suitable construction.

D is the revolving grinder on a shaft, a, that is sustained on frame A, and is to be driven by suitable power.

E is the fixed grinder, formed of plate-sections b, tied by a rod, c, and supported by cross-bars d beneath.

The revolving grinder D may be a roller or cylinder having a fluted or ribbed surface; but I prefer the construction shown, in which a hollow cylinder, e, is fixed on the shaft a, and rings f, of V form on their outer surfaces, are placed around the cylinder and clamped between end disks, g, by nuts h, that take on the hubs of cylinder e. These rings or sections f are of steel, and their beveled surfaces are grooved to form cutting-edges.

The plates of which the stationary grinders E are formed are of V form on their ends contiguous to the grinder D, and the ends enter between the rings f. The plates are curved to extend from about the horizontal center line of roller D to the under side of the roller, and I prefer that the space between the grinders D E should decrease from the upper to the

lower or delivery point. The plates b are all alike, and are tied together by a rod, c, passing through said plates, and are clamped by nuts upon the ends of the said rod. This rod c passes through bearing-blocks n at its ends. These blocks rest in boxes, (shown in dotted lines in Figs. 1 and 2,) said boxes being of greater horizontal length than the blocks, so that the rod can be moved forward or backward. Set-screws 1, 1 serve to adjust the blocks and the rod, and to hold the grinder in proper position. The grinder E may turn slightly upon the shaft c, and the front or grinding edge may be adjusted in relation to the revolving grinder D by means of the set-screws m, which pass through hangers l, and bear against bars d, extending across underneath the plates b. By means of these adjusting-screws the grinder E may be swung so as to regulate the space between it and the revolving grinder, as may be desired. The bars d, one being behind and the other in front of the bolting-rod c, serve to hold the grinder steadily in any position in which it may be set, and by the set-screws m the space between the grinding-surfaces above or below 75 may be widened or narrowed at pleasure.

Above the grinder E is fixed an inclined plate, p, that is shaped to lead the material to the grinders. Side plates, o, are also provided to confine the material at the ends of the roller D. By this construction I obtain an extent of grinding-surface equal to one-quarter the circumference of the revolving grinder, and sufficient to reduce the material at once without regrinding. There will be continual 85 reduction from the point where the material enters between the surfaces to the delivery at the under side, and the extent of reduction can be varied by adjustment. With materials that require to be coarsely ground, or simply 90 cracked, the stationary grinder will be formed of narrow plates.

The form and size of ribs on the revolving and stationary grinders may be varied, and the grooves or teeth also made in suitable 95 form, according to the materials to be ground.

Having thus described my invention, I claim as new and desire to secure by Letters Patent—

1. The combination of the revolving grinder composed of the cylinder *e* and rings *f*, provided with grinding-faces arranged upon the cylinder and held in place by the end disks, *g*, 5 as described, with the grinder *E*, composed of a series of plates bolted together with grinding-faces corresponding to those of the revolving grinder, and adjustable thereto, both horizontally and vertically, substantially as 10 described.
2. In a grinding-mill the revolving grinder *D*, in combination with the grinder *E*, composed of plates *b*, tied together by rod *c*, and provided with grinding-faces corresponding

to the revolving grinder *D*, said grinding-faces being adjustable vertically by means of set-screws *m* in the hangers *l*, substantially as described. 15

3. In a grinding-mill, the combination of a revolving grinder, *D*, and the grinder *E*, composed of plates and tie-rod *c*, as described, the said rod *c* having its bearings in adjustable blocks in the frame, substantially as described. 20
